RESEALING BOTTLE CAP OR THE LIKE

Rudolf Vogel, 1140 Laurel Ave.,
Bridgeport, Conn. 06604

Filed June 30, 1972, Ser. No. 268,107

Term of patent 14 years

Int. Cl. D9—07

U.S. Cl. D9—287

FIG. 1

FIG. 2

FIG. 3

FIG. 4

FIG. 5

FIG. 3

FIG. 4

FIG. 5

FIG. 6

FIG. 1 is a top perspective view of a resealing bottle cap showing my new design;

FIG. 2 is a bottom perspective view;

FIG. 3 is an enlarged scale top plan view;

FIG. 4 is an enlarged scale bottom plan view; and

FIG. 5 is an enlarged scale elevational view.

I claim:

The ornamental design for a resealing bottle cap or the like, substantially as shown and described.
